UNITED STATES PATENT OFFICE.

JOHN C. DAYNIX, OF PHILADELPHIA, PENNSYLVANIA.

AEROPLANE.

Application filed August 7, 1924. Serial No. 730,586.

To all whom it may concern:

Be it known that I, JOHN C. DAYNIX, a citizen of the United States, residing at Philadelphia, in the county of Philadelphia and State of Pennsylvania, have invented certain new and useful Improvements in Aeroplanes, of which the following is a specification.

This invention relates to aircraft and it has more particular reference to that type commonly designated "heavier than air flying machines", the primary object being to provide an aeroplane having an adequate maintenance surface with a relatively decreased wing spread.

Another object of this invention is to produce an aeroplane which will automatically control and utilize the air to best advantage during flight, instead of said aeroplane being, as now generally obtains, more or less controlled thereby.

A further object is to furnish an aeroplane characterized by means productive of vacuum waves and buoyancy currents so directed during flight as to ensure the maximum factor of safety, lateral stability and positive balance.

A still further object is to provide a flying machine equipped with means, for aerial flight and marine propulsion, so located as to ensure increased sustaining power, with a correlated efficiency in lifting and propelling force.

Other objects are associated in means to compress and bank air currents longitudinally of the machine with incidental increased buoyancy, and a reduction to the minimum of adverse effects liable to be set up when encountering cross currents; to provide a flying machine which can effect an aquatic landing with perfect ease and be easily navigated to suitable anchorage; to automatically stabilize the machine with maintenance on an even keel; and to produce a flying machine capable of great carrying capacity without being cumbersome and ungainly to manœuvre.

My invention further embodies all of the foregoing and other novel objects and advantages hereinafter referred to; or which will become apparent from the following detailed description of one practical form thereof, chosen from many others as well adapted to clearly exemplify and explain its

novel characteristics; while the scope of said invention is succinctly defined by the subjoined claims.

In order that those skilled in the art may fully understand this invention I have more or less conventionally shown the same in the accompanying sheets of drawings, with omission of such structural details as might be conducive to complex illustration, whereby the novel features will be better appreciated in correct perspective. In the several views of the drawings, like reference indicies are employed to designate the same or corresponding parts.

Figure 1 is a perspective view of my novel aircraft looking angularly astern.

Figure 2 is a similar view looking ahead.

Figure 3 is a longitudinal vertical section.

Figure 4 is a top plan view.

Figure 5 is a front end elevation.

Figure 6 is a somewhat enlarged detail view of the forward motor and associated controls.

Figure 7 is a similar detail view of the rear motor and marine propulsion mechanism.

Figure 8 is a detail view of an automatic stabilizer device hereinafter more fully explained; and

Figure 9 is a diagrammatic plan of the rudder control.

Referring more in detail to the drawings it will be seen that my novel aircraft comprises a fuselage 9 of approximately—though not essentially—rectangular or other tubular cross section, divided at intervals by partitions (not shown) to provide navigation, passenger, freight and other accommodation, as well as the necessary quarters for the crew and dining facilities. In addition to the foregoing a medial section of the fuselage 9 is set apart for the housing of a stabilizer instrumentality, comprehensively designated by the numeral 10, Figures 3 and 8, the same being hereinafter fully described.

The fuselage 9, as will be best seen from Figures 1, 2 and 4 is suitably nosed at its fore-and-aft ends 11, 12, respectively, while it surmounts a longitudinal tank or tanks 13, subdivided to afford storage for fuel, oil and other accessories, as well as providing adequate space to accommodate mail, baggage and other freight to be transported. This tank or tanks 13, in turn is mounted

upon a pair of longitudinally disposed and spaced pontoons 14, 14, affording therebetween a cambered tunnel 15 co-extensive and aligned with the longitudinal median line of the aircraft for a purpose later on fully set forth.

These pontoons 14, 14, it will be readily understood are preferably shaped in their sub-portions to simulate hulls effective for easy aquatic launching and navigation, while the cambered superstructure intermediate the same affords a rigid keel or backbone for the entire craft. This feature I have found of prime importance in that it serves a dual purpose; to-wit, supports the dead weight in a buoyant manner, as well as to all practical intents eliminating vibration during navigation. These pontoons 14, 14, may also be utilized as storage for compressed air or a non-inflammable gas, whereby the craft is rendered much more buoyant in flight, while they also provide housing for the landing wheels 16, that are mounted on transverse shafts 17, journaled in suitable bearings therein. At this juncture it is well to point out that the landing wheels 16 are omitted in Figures 1 and 2, as well as certain other mechanisms and instrumentalities later on particularly detailed in connection with other views, in order not to conflict with the planal structure and cause complex illustration.

Referring again to the fuselage 9 and as best shown by Figures 1, 2, 3 and 5, it will be seen that the floor or deck thereof is co-extensive and co-planal with a main plane or aerofoil 18, the longitudinal edges whereof are downwardly curved or rolled at 19 for a purpose later on explained. Mounted in superposed, but slightly declined relation to the plane or aerofoil 18, and extending fore-and-aft of the upper part of roof 20 of the fuselage 9, are what may be conveniently designated longitudinal sustaining planes 21, 21, braced at intervals by stanchions—not shown—and having their longitudinal outer edges downwardly cambered or rolled at 22 for a similar purpose to that referred to in connection with the main plane or aerofoil 18. In connection with this part of my invention, it is well to here point out when stating that the sustaining planes 21, 21 are slightly declined it is to be clearly understood that assuming the main plane or aerofoil 18 is disposed horizontal, the vertical altitude between said sustaining planes at the front end of the machine is somewhat greater than that at the rear. Or, in other words, the sustaining planes 21, 21 have a slight longitudinal declination relative to the main plane or aerofoil 18, so that when the machine is in flight parallel columns of air are slightly compressed longitudinally at each side of the fuselage 9 thereby assisting the production of a vertical suction in an up-

ward direction, as well as materially aiding stability by establishing buoyancy currents at each side of the machine. In connection with the foregoing features attention is also directed to the longitudinal and downwardly rolled edges 22 whereby the longitudinal air currents intervening the main plane or aerofoil 18 and the sustaining planes 21, 21, according to its density or rarity while slightly compressed are also inwardly banked relative to the fuselage 9. This simultaneous compressive and banking of the longitudinally aligned buoyancy currents, I have found greatly increases the general stability of the machine, while countering adverse cross currents having a tendency to disturb equilibrium or deviation from an even keel.

In combination with the sustaining wing planes 21, 21, just described, as shown by Figures 1 and 2, or in lieu thereof, as illustrated in Figures 3, 4 and 5, I fit my novel flying machine with a series of rearwardly stepped and slightly declined sustaining wing planes 23, 24, 25 similarly disposed relative to the main plane or aerofoil 18 as hereinbefore set forth. These sustaining wing planes 23, 24, 25 are, however, each fitted with a forwardly directed arcuate nose portion 26—in the art commonly designated bull-noses—hinged transversely of the machine at 27, and all capable of simultaneous and uniform adjustment, whereby the angular deflection of the buoyancy currents directed below said wing planes may be varied at will. A convenient means to accomplish this uniform adjustment of the nose portions 26, is more or less diagrammatically shown in Figure 3, and it comprises a series of bell cranks 28, fulcrumed at 29 to the fuselage 9, and connected to said nose portions by pivotal links 30. These bell cranks 28 are in turn coordinated for synchronous movement by connecting rods 31 under control of a hand or power control 32, and associated locking quadrant 33, in the pilot house at the fore part of the fuselage. In Figures 1 and 2, it will be observable that the forward wing planes 23, 24 are to all practical intent dispensed with while the wing planes 25 are considerably shorter than as indicated in Figure 3, it being obvious such arrangement is consequent upon the close relation of the wing planes 21 to the nose portions 26. Furthermore, I desire at this juncture to lay particular stress on the purpose of the sustaining planes 23, 24 and 25 with their associated nose portions 26; namely, the establishment of vacuum waves longitudinally of the upper regions of the machine which constantly create and maintain a vertical suction during flight. This phase of my invention is of primary importance as I have found that the buoyancy and carrying capacity of the machine is very materially augmented thereby.

In conjunction with the means just described for maintaining vacuum waves longitudinally of the machine, I provide a longitudinal tunnel or tube 34, co-extensive and 5 axially aligned above the roof 20 of the fuselage 9, said tube being of any convenient cross section and gradually—though not essentially so—decreased in area slightly rearwards of the machine. In the embodiment 10 of my invention, shown by Figures 1 and 2, it will be observed that this tunnel or tube 34 is interrupted transversely at 34' to accommodate the adjustable noses 26, so that each said nose portion is functional to 15 direct a column of air thereinto with more or less velocity and compressive action whereby a powerful buoyancy current is continuously maintained co-axially and longitudinally central above the fuselage roof 20 for a very obvious purpose.

Somewhat similarly I provide longitudinally at each side of the fuselage 9 open-ended tubes 35, 35 (one at each side thereof) and conveniently rectangular in cross 25 section. These tubes 35, 35, as best understood from Figure 1, are rearwardly declined for the major portion of their length and thereafter diverted at 36 upwardly in so far as their upper walls are concerned, 30 and said rear portions are fitted with adjustable shutters 37—Figures 1 and 5—functional as choke devices. It will, of course, be well understood that these shutters 37 are coordinated and normally 35 repose snugly against the underside of the upwardly inclined portions 36, so as to offer no resistance to the free flow of buoyancy currents through the tubes 35, 35; but that appropriate eccentric mechanism indicated at 40 38, and operable from the pilot house is provided, whereby they may be downwardly swung to more or less close the exit ends of said tubes. When so declined the shutters 37 will compress the buoyancy currents 45 flowing through the tubes 35, 35, such as when effecting a landing, whereby an effective retarding or braking means is supplied.

In like manner, though not essentially so, 50 the longitudinal tank or tanks 13 may be provided with supplemental buoyancy current tubes 39, 39 of similar section and declination rearwardly of the machine, but minus any choke shutters, whereby it will be readily understood that the general stability 55 of the machine is safeguarded and the buoyancy capacity increased to the maximum.

Stabilizer wings 40, 41, are fitted at each 60 side of the fuselage and fore-and-aft thereof respectively, said wings being coordinated with and independently operable of or automatically controlled by the stabilizer device 10, hereinbefore referred to. This stabilizer device 10 comprises a pendulum chamber 42, universally suspended at 43 and having sufficient cubic capacity to afford storage for

dead weight material, or two or more passengers. Vertically of the pendulum chamber 42, and best shown in Figure 8, is a rigid post 44 affording pivotal bearing at 45 for a double-armed rocker 46 provided with 70 arcuate slots 47 affording sliding guidance for bearers 48, to which a longitudinal rod or rods 49, 50 are pivoted, and in turn co-ordinated by rocker arms 51 with the axles of the aforesaid stabilizer wings 40, 41, respectively. The rod 49 it will be seen from Figure 3 is forwardly extended and connected to a hand or power control 52, afforded bearing at 53 in the pilot house, as will be readily understood without further 75 explanation. Connecting with the bearers 48 aforesaid is a convergent toggle linkage 54, having suitable vertical guidance and connected by a short link 55 with one arm of a bell-crank 56, fulcrumed at 57, to a lateral arm 58, on the rigid post 44; the other arm of said bell-crank being coordinated by a rod 59 to a manual or power control and associated lock quadrant—comprehensively designated 60.

Elevating rudders 61, 61, are fitted to the main plane or aerofoil 18, and are movable through the medium of rocker arms 62 co-ordinated by an appropriate connection 63 with a control lever 64, in the well known 95 way; hence a more elaborate detailed description thereof is omitted.

In addition to the foregoing instrumentalities for ensuring perfect stability and control of the machine in flight, and by way of clarifying a distinction existent in the stabilizing means, it is noteworthy that when the several parts occupy the positions shown in Figure 8 the aviator or pilot can freely manipulate the stabilizer wings 41 from the control 52. On the other hand, by elevating the bearers 48 until they are on a dead level with the bearing pivot 45 by manipulating the control 60, or as indicated by the dot-and-dash line shown across Figure 8, the stabilizer 10 as a unit will become automatically effective and function to maintain perfect equilibrium during flight, as will be readily understood by those conversant with the art.

The steering rudder 65 is pivotally supported by a rudder post 66 at the rear end of the machine, and in alignment with said post is a fixed rudder 67 whereby effective steerage under all service conditions is positively attained. Pivotally connected at 68 to lateral arms 69—Figure 9—on the steering rudder 65 are crossed rods or cables 70, suitably guided and pivotally connected at 71 with corresponding arms 72 secured to the axis 73 of a pilot rudder 74 partly associated in a forwardly stationed open ended and rearwardly convergent tube 75, surrounding the hereinbefore described tunnel or tube 34. Forwardly extended from one

of the crossed rod or cable pivotal connections to the arms 72, is a rod 76 coordinated with a control lever 77, whereby the rudders 67, 74 are movable in reverse relation, and it will be readily understood that when said rudders are in neutral position, a column of slightly compressed air will be directed longitudinally rearwards of the upper surface of the machine that tends to substantially 10 increase the vacuum suction essential to perfect buoyancy of heavier than air machines.

The motors 78, 78', for my improved flying machine are preferably disposed fore and aft thereof in direct alignment with the longitudinal axis, and they are mounted securely under the main plane or aerofoil 18 above the cambered tunnel 15 whereby a firm and stable base is afforded therefor. Furthermore, by locating the motors 78, 78', as just set forth, it will be clear that vibratory disturbance inherent thereto is concentrated at the most invulnerable part 20 of the machine, whereby the factor of safety in general is very materially increased. Incidentally it is to be remarked that the fore and aft propellers 79, 80, respectively, are draught and drive propellers whereby maximum speed in flight is ensured. Again 30 the motors 78, 78', are, or may be, of any approved type, it being understood that the showing in Figures 1 and 2 is purely diagrammatic and entirely disproportionate in so far as capacity and size is concerned; the 35 drawings having been made from photos of an accurately scaled model fitted with electric motors to test its behaviour in flight, and accordingly many times too large when the machine is considered from a full-size viewpoint. These motors 78, 78' are coordinated or clutched together to operate what may be broadly termed composite launching and aquatic propelling means. To this end the 40 power shafts 81, 82 of the motors 78, 78' are inwardly extended and journaled in bearings 83, said shafts being fitted with feathered clutch members 84, connected for simultaneous movement, through the medium of a longitudinal shifter rod 85, having 45 forked engagement therewith. This shifter rod 85 is under the control of a lever 86 and associated lock quadrant 87 of any approved type.

As best shown by Figure 6, the forward motor 78 and associated clutch 84 is adapted to operate a bevel couple 88 in turn serving to rotate a vertical shaft 89, and through a second bevel drive 90, revolve the shaft 17 on which the forward landing wheels 16 are mounted. Similarly the rear or after motor 78' and associated clutch 84 is adapted to couple a bevel drive 91 operative to rotate a vertical shaft or shafts 92, in turn 50 geared at 93 with horizontally journaled shafts 94, fitted with marine propellers 95,

adapted to progress the machine when navigating in water or making a forced landing thereon. Incidentally, it may be mentioned that the peaks of the pontoons 14 are given suitable stream lines and appropriate rake, 70 to facilitate easy marine navigation while the sterns are butted, as best indicated in Figure 3 to afford proper bearing for the propellers 95.

Associated in a machine constructed and arranged for aerial and aquatic propulsion as described and shown, I may provide a sub-plane for side wings 96, 96, co-extensive with the top of the pontoons 14, 14, and having their longitudinal edges downwardly 80 rolled at 97, and said plane or wings may be braced to the main plane or aerofoil 18 by stanchions 98 or appropriate guys. The object and function of the sub-plane or wings 96, 96 is in a measure self-evident, 85 but it may be briefly stated that it serves a dual purpose; namely, when the machine is in aerial flight it materially increases the sustaining power while when said machine is being navigated on water it augments the 90 buoyancy by banking air thereunder. To a similar degree the arched tunnel 15 compresses a column of air therein when the machine is on water, while when in aerial flight, consequent upon the specific position 95 of the draught and drive propellers 79, 80, it will be readily appreciated that a buoyancy current is directly trained therethrough with obviously added flight efficiency, as well as in a sense lending compressive support co-extensive with the backbone or keel of the machine.

In addition to all the foregoing instrumentalities and means for ensuring perfect buoyancy and automatic control, I may provide the sustaining planes 23, 24, 25 on their upper surfaces with longitudinally directed T-section suction devices or rigid ailerons 99, Figures 4 and 5; the horizontal surfaces whereof are provided with perforations 100 that may be fitted with downwardly closing non-return valves whereby an added elevating impetus is ensured, as will be apparent to any one in the least acquainted with aerodynamics. It is also to be remarked that the horizontal portions of the suction devices 99 are preferably longitudinally cambered, as shown clearly in Figure 5, to more effectively trap and bank the suction currents.

From the foregoing description and on examination of the drawings it is thought that the inherent advantages and manner of manipulating, controlling and navigating my novel flying machine will be fully understood without repetitive description. Furthermore, while I have detailed a particular construction, combination and aggroupment of the several features involved, 125 it is to be distinctly understood this specification includes within its purview diversi- 130

fied variations and modifications too numerous to enumerate. Accordingly the right is hereby reserved to include all such reasonable and other detail changes that fairly come within the scope of the appended claims.

Finally, it will be quite clear from the foregoing that a flying machine embodying the structural features set forth, includes an adequate sustaining area; is of maximum stability and buoyancy; while the vacuum waves and buoyancy currents are so directed and correlated as to ensure absolute safety at all times, no matter what the flight conditions may be.

Having described my invention what I claim is:—

1. A flying machine including a main aerofoil with the major dimension lengthwise and superposed vacuum wave producing minor planes having a rearward declination, and provided with adjustable noses.

2. A flying machine including a main aerofoil with the major dimension lengthwise, and superposed vacuum wave producing minor planes having a rearward declination, and adjustable arcuate section noses.

3. A flying machine including a main aerofoil with the major dimension lengthwise, and superposed vacuum wave producing minor planes having a rearward declination, and coordinated hinged bull noses.

4. A flying machine including a main and superposed sustaining wing planes with the major dimension lengthwise and adjustable vacuum wave producing means associated above the wing planes.

5. A flying machine including a main and superposed sustaining wing planes with the major dimension lengthwise and coordinated adjustable laterally disposed arcuate means having capacity to produce vacuum waves.

6. A flying machine including a main aerofoil with the major dimension lengthwise of said machine, adjustable superposed vacuum wave producing lateral planes, a buoyancy current passage co-extensive with the machine intersected by the lateral planes, and a sub-plane with associated pontoons.

7. A flying machine including a main aerofoil with the major dimension lengthwise of said machine, adjustable superposed vacuum wave producing lateral planes, a buoyancy current passage co-extensive with the machine intersected by the lateral planes, and a sub-plane with underlying pontoons affording an arched keel for the purpose specified.

8. A flying machine including a main aerofoil with the major dimension lengthwise of said machine, superposed adjustable vacuum wave producing lateral planes with an associated buoyancy current passage, and suction devices mounted above the lateral planes.

9. A flying machine including a main aerofoil with the major dimension lengthwise of said machine, superposed adjustable vacuum wave producing lateral planes with an associated buoyancy current passage, and T-section suction devices mounted above the lateral planes.

10. A flying machine including a main aerofoil with the major dimension lengthwise of said machine, superposed adjustable vacuum wave producing lateral planes with an associated buoyancy current passage, and longitudinally directed T-section suction devices mounted above the lateral planes.

11. A flying machine including a main aerofoil with the major dimension lengthwise of said machine, superposed adjustable vacuum wave producing lateral planes with an associated buoyancy current passage, and suction devices mounted above the lateral planes, said main and lateral planes as well as the suction devices having the longitudinally directed edges thereof downwardly rolled.

12. A flying machine including a main supporting plane with the major dimension lengthwise thereof, a fuselage and surmounted co-extensive buoyancy current tube, laterally directed rearwardly declined wing planes adjacent the top of the fuselage, and air tight pontoons below the machine affording an arched keel.

13. A flying machine including a main supporting plane with the major dimension lengthwise thereof, a fuselage and surmounted co-extensive buoyancy current tube, laterally directed rearwardly declined wing planes having adjustable noses intersecting the buoyancy tube, and airtight pontoons below the machine affording an arched keel.

14. A flying machine including a main supporting plane with the major dimension lengthwise thereof, a fuselage and surmounted co-extensive buoyancy current tube, laterally directed rearwardly declined interlapping wing planes having coordinated adjustable noses intersecting the buoyancy tube, and airtight pontoons below the fuselage affording an arched keel.

15. A flying machine having a main aerofoil with the major dimension lengthwise thereof, and superposed vacuum wave producing laterally directed minor planes, said minor planes slightly overlapping each other at the adjacent ends.

16. A flying machine having a main aerofoil with the major dimension lengthwise thereof, and superposed vacuum wave producing laterally directed and rearwardly declined minor planes, said minor planes slightly overlapping each other at the adjacent ends.

17. A flying machine having a main aerofoil with the major dimension lengthwise

thereof, and superposed vacuum wave producing laterally directed and rearwardly declined minor planes, said minor planes slightly overlapping each other at the adjacent ends, and having longitudinally directed suction devices on their upper faces.

18. A flying machine including a main aerofoil with the major dimension lengthwise thereof, a fuselage and surmounted co-extensive buoyancy current tube, laterally directed rearwardly declined wing planes having adjustable noses adjacent the top of the fuselage, parallel airtight pontoons below the fuselage affording an arched keel, and a supplemental buoyancy current tube at each side of the fuselage.

19. A flying machine including a main aerofoil with the major dimension lengthwise thereof, a fuselage and surmounted co-extensive buoyancy current tube, laterally directed rearwardly declined wing planes having adjustable noses adjacent the top of the fuselage, parallel airtight pontoons below the fuselage affording an arched keel, and a supplemental buoyancy current tube at each side of the fuselage, said supplemental tubes being fitted with coordinated adjustable shutters for the purpose specified.

30 20. A flying machine including a main aerofoil with the major dimension lengthwise thereof, a fuselage and surmounted co-extensive buoyancy current tube, laterally directed rearwardly declined wing planes having adjustable noses adjacent the top of the fuselage, a sub-plane below the fuselage having parallel airtight pontoons thereunder affording an arched keel, and a supplemental buoyancy current tube at each side of said fuselage.

21. A flying machine including a main aerofoil with the major dimension lengthwise thereof, a fuselage and surmounted co-extensive buoyancy current tube, laterally directed rearwardly declined wing planes having adjustable noses adjacent the top of the fuselage, a sub-plane below the fuselage having parallel airtight pontoons thereunder affording an arched keel, and a supplemental buoyancy current tube at each side of said fuselage, the supplemental tubes having coordinate adjustable shutters for the purpose specified.

55 22. A flying machine including a main aerofoil with the major dimension lengthwise thereof, a fuselage and surmounted co-extensive buoyancy current tube, laterally directed rearwardly declined wing planes having adjustable noses adjacent the top of the fuselage, storage capacity below the fuselage having co-extensive buoyancy tubes, a sub-plane and parallel airtight pontoons thereunder affording an arched keel, and a supplemental buoyancy current passage at each side of the fuselage fitted with

coordinate adjustable shutters for the purpose specified.

23. A flying machine including a main aerofoil with the major dimension lengthwise thereof, a fuselage and surmounted co-extensive buoyancy current tube, laterally directed rearwardly declined wing planes having coordinated adjustable nose portions adjacent the top of the fuselage, a sub-plane and parallel airtight pontoons below the fuselage, a supplemental buoyancy current tube at each side of the fuselage and longitudinal thereof, landing wheels and marine propellers associated with the pontoons, and means whereby said wheels and propellers may be operated to facilitate an easy ascent and effect hydronavigation respectively.

24. A flying machine including a main aerofoil with the major dimension lengthwise thereof, a fuselage and surmounted co-extensive buoyancy current tube, laterally directed rearwardly declined wing planes having coordinated adjustable nose portions adjacent the top of the fuselage, a sub-plane and parallel airtight pontoons below the fuselage, a supplemental buoyancy current tube at each side of the fuselage and longitudinal thereof, lateral stabilizer wings for the machine, and means coordinating deflection of said wings to assist ascent and landing.

25. A flying machine including a main aerofoil with the major dimension lengthwise thereof, a fuselage and surmounted co-extensive buoyancy current tube, laterally directed rearwardly declined wing planes having coordinated adjustable nose portions adjacent the top of the fuselage, a sub-plane and parallel airtight pontoons below the fuselage, a supplemental buoyancy current tube at each side of the fuselage and longitudinal thereof, lateral stabilizer wings for the machine and a coordinated stabilizing device whereby said wings may be automatically controlled during flight to maintain the machine in equilibrium.

26. A flying machine including a main aerofoil with the major dimension lengthwise thereof, a fuselage and surmounted co-extensive buoyancy current tube, laterally directed rearwardly declined wing planes having coordinated adjustable nose portions adjacent the top of the fuselage, a sub-plane and parallel airtight pontoons below the fuselage, a supplemental buoyancy current tube at each side of the fuselage and longitudinal thereof, lateral stabilizer wings for the machine, a coordinated stabilizing device whereby said wings may be automatically controlled during flight to maintain the machine in equilibrium, and independent operating mechanism for effecting manual control of the stabilizing wings.

27. A flying machine including a main aerofoil with the major dimension length-

- wise thereof, a fuselage and surrounded co-extensive buoyancy current tube, laterally directed rearwardly declined wing planes having coordinated adjustable nose portions 5 adjacent the top of the fuselage, a sub-plane and parallel airtight pontoons below the fuselage, a supplemental buoyancy current tube at each side of the fuselage and longitudinal thereof, elevating rudders on the 10 main aerofoil, and means whereby said elevating rudders are simultaneously operated. 28. A flying machine including a main aerofoil with the major dimension lengthwise thereof, a fuselage and surmounted co-extensive buoyancy current tube, laterally directed rearwardly declined wing planes having coordinated adjustable nose portions adjacent the top of the fuselage, a sub-plane and parallel airtight pontoons below the 15 fuselage, a supplemental buoyancy current tube at each side of the fuselage and longitudinal thereof, a main steering rudder, and an air compressing device provided with a pilot rudder at the fore part of the machine. 20 29. A flying machine including a main aerofoil with the major dimension lengthwise thereof, a fuselage and surmounted co-extensive buoyancy current tube, laterally directed rearwardly declined wing planes 25 having coordinated adjustable nose portions adjacent the top of the fuselage, a sub-plane and parallel airtight pontoons below the fuselage, a supplemental buoyancy current tube at each side of the fuselage and longitudinal thereof, elevating rudders on the main aerofoil, means whereby said rudders are simultaneously operated, a main steering rudder, and a coordinated pilot rudder at the fore part of the machine, a main steering rudder, an air compressing tube and associated pilot rudder at the upper fore part of the machine, and mechanism reversely co-ordinating movement of the main and pilot rudders. 30 35 30. A flying machine including a main aerofoil with the major dimension lengthwise thereof, a fuselage and surmounted co-extensive buoyancy current tube, laterally directed rearwardly declined wing planes having coordinated adjustable nose portions adjacent the top of the fuselage, a sub-plane and parallel airtight pontoons below the fuselage, a supplemental buoyancy current tube at each side of the fuselage and longitudinal thereof, a main steering rudder, and an air compressing device provided with a pilot rudder at the fore part of the machine, said pilot rudder being adapted for simultaneous but reflex movement with respect to 40 the main steering rudder. 30. A flying machine including a main aerofoil with the major dimension lengthwise thereof, a fuselage and surmounted co-extensive buoyancy current tube, laterally directed rearwardly declined wing planes 45 having coordinated adjustable nose portions adjacent the top of the fuselage, a sub-plane and parallel airtight pontoons below the fuselage, a supplemental buoyancy current tube at each side of the fuselage and longitudinal thereof, elevating rudders on the main aerofoil, means whereby said rudders are simultaneously operated, a main steering rudder, and a coordinated pilot rudder at the fore part of the machine. 50 55 31. A flying machine including a main aerofoil with the major dimension lengthwise thereof, a fuselage and surmounted co-extensive buoyancy current tube, laterally directed rearwardly declined wing planes having coordinated adjustable nose portions adjacent the top of the fuselage, a sub-plane and parallel airtight pontoons below the fuselage, a supplemental buoyancy current tube 55 at each side of the fuselage and longitudinal thereof, elevating rudders on the main aerofoil, means whereby said rudders are simultaneously operated, a main steering rudder, and a coordinated pilot rudder at the fore part of the machine. 60 65 32. A flying machine including a main aerofoil with the major dimension lengthwise thereof, a fuselage and surmounted co-extensive buoyancy current tube, laterally directed rearwardly declined wing planes having coordinated adjustable nose portions adjacent the top of the fuselage, a sub-plane and parallel airtight pontoons below the fuselage, a supplemental buoyancy current tube at each side of the fuselage and longitudinal thereof, elevating rudders on the main aerofoil, means whereby said rudders are simultaneously operated, a main steering rudder, and a coordinated pilot rudder at the fore part of the machine, said pilot rudder being adapted for simultaneous but reflex deflection relative to the main steering rudder. 70 75 80 85 90 95 100 105 110 115 120 125 130

fuselage, a supplemental buoyancy current tube at each side of the fuselage and longitudinal thereof, draught and drive propellers at the fore and after ends of the machine in direct alignment above the keel line thereof, landing wheels and marine propellers associated with the pontoons, a source of rotative power for each propeller aforesaid, and means for coordinating operation of the landing wheels and marine propellers to aid ascent and provide for hydro-navigation respectively.

36. A flying machine including a main aerofoil with the major dimension lengthwise thereof, a fuselage and surmounted co-extensive buoyancy current tube, laterally directed rearwardly declined wing planes having coordinated adjustable nose portions adjacent the top of the fuselage, a sub-plane and parallel airtight pontoons below the fuselage, a supplemental buoyancy current tube at each side of the fuselage and longitudinal thereof, draught and drive propellers at the fore and after ends of the machine in direct alignment above the keel line thereof, landing wheels and marine propellers associated with the pontoons, a source of rotative power for each propeller aforesaid, and clutching mechanism coordi-

nating rotation of the landing wheels and marine propellers to aid ascent and provide for hydronavigation respectively.

37. A flying machine including a main aerofoil with the major dimension lengthwise thereof, a fuselage and surmounted co-extensive buoyancy current tube, laterally directed rearwardly declined wing planes having coordinated adjustable nose portions adjacent the top of the fuselage, a sub-plane and parallel airtight pontoons below the fuselage, a supplemental buoyancy current tube at each side of the fuselage and longitudinal thereof, lateral stabilizer wings for the machine, means whereby said wings may be automatically or manually controlled to maintain the machine in equilibrium, landing wheels and marine propellers associated with the pontoons, a source of rotative power for each propeller aforesaid, and means for coordinating operation of the landing wheels and marine propellers to aid ascent and provide for hydro-navigation respectively.

Signed at Philadelphia, in the county of Philadelphia and State of Pennsylvania, the 4th day of August, 1924.

JOHN C. DAYNIX.
